UNITED STATES PATENT OFFICE

140,276

DESIGN FOR A POSITION SELECTOR AND INDICATOR FOR MOVABLE PARTS OF AN AIRCRAFT OR SIMILAR ARTICLE

William P. Lear, North Hollywood, Calif., assignor, by mesne assignments, to Lear, Incorporated, Piqua, Ohio, a corporation of Illinois

Application November 22, 1943, Serial No. 111,760

Term of patent 14 years

(Cl. D26—5)

To all whom it may concern:

Be it known that I, William P. Lear, a citizen of the United States of America, residing at North Hollywood, in the county of Los Angeles, in the State of California, have invented a new, original, and ornamental Design for a Position Selector and Indicator for Movable Parts of an Aircraft or Similar Article, of which the following is a specification, reference being had to the accompanying drawing, forming a part thereof.

In the drawing:

Fig. 1 is a side elevational view of position se-

lector and indicator for movable parts of an aircraft or similar article embodying the present design.

Fig. 2 is a top plan view.

Fig. 3 is a front elevational view.

Fig. 4 is a rear elevational view thereof.

I claim:

The ornamental design for a position selector and indicator for movable parts of an aircraft or similar article, substantially as shown.

WILLIAM P. LEAR.
